UNITED STATES PATENT OFFICE.

LILLIAN WITHERSPOON, OF SAN FRANCISCO, CALIFORNIA.

FACIAL APPLIANCE.

Application filed March 26, 1925. Serial No. 18,464.

This invention relates to an appliance for lifting, molding and correcting facial defects.

The object of the present invention is to generally improve and simplify the construction and operation of appliances of the character described; to provide an appliance that will eliminate all pressure on the nose or across the upper lip; to provide an appliance or mask whereby pressure may be applied to different portions of the face just where needed or desired; to provide a snugly fitting mask adapted to cover practically all of the face, chin and neck; and further, to provide means whereby it may be quickly and readily adjusted and secured against displacement while in use.

One form which my invention may assume is exemplified in the following description and illustrated in the accompanying drawings, in which—

Fig. 1 is a front view showing the application of the mask.

Fig. 2 is a side elevation of the same.

Fig. 3 is a plan view showing the mask and attaching tabs laid out flat.

Referring to the drawings in detail, and particularly to Fig. 1, it will be noted that the appliance consists of a body or face section from which are extended or attached fourteen straps or adjusting ties. A lesser number of straps could be used, but a less number of straps would lessen the effectiveness also. There are three sets of loops through which various ties pass, thus preventing any displacement of the straps when applied to the head of the wearer.

Particular attention is called to straps 1, 1^a, 2 and 2^a. Straps 1 and 1^a may be cut in one with the balance of the appliance, and straps 2 and 2^a attached at the point where the neck and chin join, as shown in Fig. 3, or just the opposite course may be pursued.

Particular attention is also directed to straps or ties 6 and 6^a. While these two straps could be cut in one with the face section and folded in under and upwardly, it will be noted that separate straps are attached for two reasons; the first and main reason being that if the balance of the straps are to be wide, as desired, on both sides of straps 6 and 6^a, there would not be enough material left at this point to produce a sufficiently wide and strong strap. The second reason is that if a tie has to be

folded in a manner necessary to obtain a strap running at right angles to straps 5 and 5^a, it would not only be more difficult to accurately fold such straps, but it would be less strong, as the folding under and upward leaves a bias angle which would probably cause an uneven pull when adjusting the mask.

Strap 9 is attached directly over strap 8 at a point about the top of the head and extends to within two or three inches of the end of strap 8.

The following procedure in tying or adjusting the mask is suggested. Straps 3 and 3^a are the first to be tied and they are tied at the back of the neck. This tie forms sort of a holding base for the second and subsequent ties. Strap 8 is next grasped and brought up before the face and then pulled back and over the head. The end of the strap is passed underneath the tie formed by the straps 3 and 3^a and is then pulled upwardly. By pulling this strap, an upward adjustment is made over the entire surface from the point where the neck and chin join at the front.

When strap 8 has been pulled sufficiently to adjust the eyes and nose openings properly, it is tied to strap 9, thus maintaining the adjustment obtained. Straps 5 and 5^a are then brought back and run through the two lower loops 12 and 12^a, which are attached to the strap 8. They are then pulled to the required adjustment and tied, and loops 12 and 12^a preventing any shifting of the straps. Straps 6 and 6^a are then pulled upwardly and passed through the loops 11 and 11^a, also attached to strap 8 at a point about the top of the head of the wearer. They are pulled to the required adjustment and tied, the loops 11 and 11^a similarly preventing any displacement of the straps. Strap 7 is then brought back and tied to strap 4^a, which is brought upwardly to meet it. Strap 7^a is also brought back and tied with strap 4, which is brought back and upwardly to meet it. Straps 2 and 2^a, which is really one long strip, are then lifted up under the chin and the ends brought up above the sides of the face and through loops 10 and 10^a. They are then pulled to proper position and tied. Straps 1 and 1^a are then brought back and tied at the back of the neck and this completes the entire adjustment.

The main section of the appliance or mask

portion which covers the face of the wearer is, as already stated, provided with two openings for the eyes, as shown in Fig. 3, and an elongated opening which extends from the bridge of the nose to a point between the lower lip and the point of the chin, this elongated opening permitting exposure of the nose and portions of the lips or all of the lips, as may be desired, thus preventing flattening of the nose or lips when pressure is applied by pulling and tying the straps.

It should be noted that the majority of the straps are formed integral with the mask section and that they have considerable width. This is important as they will in this manner cover practically every portion of the entire circumference of the mask, thus giving an even pull over the entire surface of the mask.

Straps of the length and width indicated could be attached separately and would probably cost less, but such method of attaching has not proven exactly efficient. The idea of cutting most of the straps in one with the face mask insures an absolutely even thread pull at the most important points, whereas separate straps or ties could hardly be applied with such thread position.

Numerous straps permit practically any pressure or pull desired to be applied to different portions of the face, this being obviously important as it thus provides means whereby the face may be lifted, molded or shaped as desired or facial defects corrected.

The device when applied is secured against displacement by the numerous straps, and the individual straps are so intertwined and looped that they themselves will not be readily displaced.

While I have shown the preferred form of my invention as now known to me, it is to be understood that various changes may be made in its construction without departing from the spirit of the invention as defined in the appended claims.

Having thus described my invention, what I claim and desire to secure by Letters Patent is:

1. A facial appliance comprising a mask of flexible material adapted to cover the face and having openings therein for the eyes and also a relatively narrow, longitudinally directed, common opening for the lips and substantially the entire nose, and means co-operating with the mask for expanding said openings to fit around the eyes, nose and lips and for securing the mask snugly to the face of a wearer without exerting pressure upon the wearer's eyes, nose or across the lips or beneath the nose.

2. A facial appliance comprising a mask of flexible material adapted to cover the face and having openings therein for the eyes and also a relatively narrow, longitudinally

directed, common opening for the lips and substantially the entire nose, and means cooperating with the mask for expanding said openings to fit around the eyes, nose and lips and for securing the mask snugly to the face of a wearer without exerting pressure upon the wearer's eyes, nose or lips, said means including neck straps and rearwardly directed back straps above the neck straps, and a head strap passed under the back straps and adapted to be pulled upwardly at its rear end over said back straps, and means to secure the head strap to maintain it in its pulled up position.

3. A facial appliance comprising a mask adapted to cover the face and having openings formed therein for the eyes and a common opening for the lips and substantially the entire nose so as to take the shape of the face snugly when drawn upon the face without exerting pressure upon the facial parts specified, straps extending from the mask adapted to be tied at the back of the neck of the wearer, a head strap extending from the mask backwardly over the head and under the aforesaid straps and pulled upwardly to adjust the mask snugly over the face to properly position the eyes, nose and mouth openings of such facial parts, means whereby to maintain the adjustment thus obtained, separate sets of loops on said second mentioned strap, a set of straps extending from the mask above the first mentioned set of straps adapted to be secured in one set of said loops, a set of straps extending from said second set of straps adapted to be secured in the other set of loops on said head strap, other sets of straps adapted to be tied together, chin straps adapted to be fitted under the chin and extend up along the sides of the face over the mask and tied together at the top of the wearer's head, and neck straps below the first mentioned set of straps adapted to be tied together at the back of the wearer's neck.

4. A facial appliance comprising a mask of flexible material adapted to cover the face, and having openings therein for the eyes and also a relatively narrow, longitudinally directed, common opening for the lips and substantially the entire nose, and means cooperating with the mask for expanding said openings to fit around the eyes, nose and lips and for securing the mask snugly to the face of a wearer without exerting pressure upon the wearer's eyes, nose or lips, said means including neck and chin and other straps and loops on certain straps through which other straps are passed to prevent displacement of the straps when the mask is worn.

LILLIAN WITHERSPOON.

CERTIFICATE OF CORRECTION.

Patent No. 1,668,794.

Granted May 8, 1928, to

LILLIAN WITHERSPOON.

It is hereby certified that error appears in the printed specification of the above numbered patent requiring correction as follows: Page 2, line 60, claim 1, strike out the word "or"; and that the said Letters Patent should be read with this correction therein that the same may conform to the record of the case in the Patent Office.

Signed and sealed this 10th day of July, A. D. 1928.

(Seal)

M. J. Moore,
Acting Commissioner of Patents.
